DIE-CASTING APPARATUS

Anton F. Waltz, Flushing, N. Y., assignor to
Edgar N. Dollin, Malba, N. Y.

Application April 20, 1931, Serial No. 531,322

5 Claims. (Cl. 22—68)

This invention relates to die-casting apparatus and more particularly to the dies and means for cooperation therewith in effecting die-casting operations.

5. Heretofore, in die-casting practice in general, various disadvantageous conditions have been encountered such, for example, as: the presence of impurities in the castings due to solution of iron from the apparatus as a result of the high 10 temperature of the alloys required to enable them to be forced into the dies so as to fill the latter satisfactorily, failure to obtain the requisite solidity of castings, and the existence of sprues of excessive size.

15. An important object of the present invention is to provide improved means for effecting die-casting operations. Another object is to provide die-casting means whereby the above mentioned and other disadvantages will be obviated.

20. Further objects are to provide die-casting apparatus especially adapted to cast metals or alloys at temperatures at which they flow thickly, apparatus in which the pressure on the flowing metal is applied close to the casting and there is 25 minimum travel under pressure of the material being cast, and apparatus adapted for supplying the casting material to the casting cavities through one or a plurality of gates or lines of supply.

30. The apparatus of the present invention is adapted to operate on the usual metals and alloys adapted for die casting and upon alloys such as brass, which could not be cast by use of the apparatus hitherto in use. The general die-casting industry here and abroad employs a submerged pressure chamber made of cast iron and pressure is generated either with compressed air or gas or with a piston and cylinder. Brass can 35 not be cast practically with submerged pressure chambers, goosenecks in the ordinary pneumatic-type machine, because of the high temperature required, about 2000° F. Brass can, however, be die-cast by the displacement means of the present invention, since it can be run in at a lower 40 temperature, that is, not above 1600° F., at which it is semi-plastic and will flow under high pressure such as a pressure of from 2000 to 3000 pounds per square inch. At higher temperatures commercial die life cannot be obtained but at not to exceed 1600° F. reasonable life and commercial application of the brass die-casting process for brass and other alloys is feasible. The high pressure used also permits casting metals and alloys at lower temperatures than before and re-

Also in the apparatus of the present invention there is no submerged chamber or goose-neck of cast iron thus substantially avoiding the usual difficulties arising from the tendency of the iron to dissolve in the hot alloys. Solution of iron 60 from the apparatus may be avoided by the use of aluminum, but the aluminum is in many instances a harmful constituent. For example, aluminum is objectionable, in connection with zinc, from the standpoint of corrosion.

65. Aluminum in zinc or zinc-alloy castings causes intercrystalline oxidation or grain growth which makes the metal weak and brittle resulting in warpage and cracking. This action is induced by galvanic action and hence is more rapid in 70 hot moist climates or in the presence of moisture or saline solutions. Steam causes rapid failure and is used for artificial aging tests. Most commercial zincs contain lead and cadmium which are especially harmful in the presence of 75 aluminum and in consequence the die-casting industry to produce castings which will be usable, must use 99.99 pure zinc, whereas with our process by eliminating aluminum lower grades of zinc can be used.

80. When the aluminum is eliminated a wide range of superior zinc alloys can be cast and this is made possible by the elimination of the submerged pressure chamber and consequent complications caused by the absorption of iron.

85. The absorption of iron is also harmful in casting aluminum alloys as it makes them corrosive, brittle and weak. Much greater resistance to corrosion and higher physical characteristics can be produced in the aluminum series by the elimination of iron and employment of high pressure and quick chilling.

90. Other features and advantages will appear upon consideration of the following description and of the drawing in which:—

95. Fig. 1 is an elevation of one form of apparatus embodying the invention; and

Fig. 2 is a top plan view of the structure shown in Fig. 1.

100. Referring to the drawing in detail, 75 and 76 designate end frames of which the frame 75 may be referred to as the front frame and 76 as the rear frame. The top of the rear frame 76 is connected by a guide member 77 with the front frame 75 at the corresponding level. As here shown the guiding member 77 is in the form of a bolt which has at its front end a reduced portion 78 passing through a corresponding bore in the frame 75 and at its rear end a correspond 105

110. sues in less porosity and better finish.

ing reduced rear portion 79 which passes through a corresponding bore in the upper end of the rear frame 76.

The shoulder at the end of the reduced portion 78 may not rest directly against the rear side of the front frame 75 but, as here shown, a washer 80 is interposed between the shoulder and the frame. At the other side of the frame 75 the reduced end 78 is provided with a suitable screw 10 thread to cooperate with a nut 81 which may engage the front face of front frame 75 but preferably is separated therefrom by a washer 80 similar to that used at the other or rear face of the front frame. The upper end of the front frame 75 is also connected by means of a guide 82, preferably of the same general form as bolt 77, with a member 83 mounted at its lower end on the reduced portion 79 of the bolt 77, which reduced portion extends through the top of the rear frame 76. The shoulder formed at one end of the reduced portion 79 of the bolt 77 may engage the front face of the member 83, the rear end of the reduced portion 79 being threaded to receive a nut 85 which may engage the rear face of the frame 76 or may be separated therefrom by means of a washer 86. To hold the member 83 from swinging downwardly around the reduced portion 79 of the bolt 77, it is provided with a suitable bore registering with a similar bore in the frame 76 so that the member 83 and the frame 76 may conveniently be fastened together by suitable means such as a screw or bolt 89.

The member 83 serves as a holder for a stationary die 90 which is secured thereto in any suitable manner. Cooperating with the fixed die 90 is a movable die 91 supported to move horizontally toward and from the fixed die 90 by means including an ejector box 92 connecting it with a movable die-holder 93 slidably mounted at the bottom and top on the bolts or guides 77 and 82, respectively.

Actuation of the movable die support or holder 93 may conveniently be effected by means of an arm 94 suitably connected, as by means of a key 95, with a shaft 96, rotatably mounted in a member 97, which in turn is mounted on the bolts 77 and 82. To enable adjustment thereof toward and from the frame 75 for purposes to be brought out hereinafter, the member 97 is secured by means of nuts 98 co-operating with the screw threaded surfaces of the guide bolts 77 and 82 and engaging member 97 on opposite sides. Mounted on the shaft 96 at opposite sides of the member 97 are toggle arms 99 which at their other ends are connected by pivots 100 with links 101 pivoted in turn to the movable die support 93 by pivots 102. Obviously, counter-clockwise swinging of the arm 94 to its left position, as viewed in Fig. 1, will straighten the toggle comprising the arms 99 and 101, and swinging of the arm 94 in the clockwise direction will release the toggle. Although the movement of the movable die-holder 93 might be effected by a single toggle such as that just described, it is desirable to actuate the holder at both top and bottom simultaneously. Accordingly the toggle just described is connected with the member 97 and the die-holder 93 at points which are nearly at the same level as the bolt 82, and similar toggle member are provided at substantially the level of the bolt 77, the arms 99 of these lower toggles being connected with the member 97 in a suitable manner, as by a suitable pivot or pivots 103 instead of a shaft corresponding to the shaft 96.

To effect corresponding and simultaneous movements of the upper and lower toggles on each side, provision is made of suitable means, such as a link 104, having its upper end pivoted at 105 to a lug 106 extending downwardly from the upper toggle arm 99 and having its lower end connected by a pivot 107 with a corresponding lug 106 projecting downwardly from the corresponding lower toggle arm 99. Obviously, adjustment of the member 97 toward or from the frame 75 will vary the toggle action. 80 85

It will be evident that upon swinging the arm 94 in a counter-clockwise direction to separate the dies the link 104 will tend to engage the lower pivot 103. Therefore, to permit movable die 91 to be withdrawn to a suitable distance from the fixed die member 90, each link 104 may be so shaped as to provide a recess at its front side at the point where the link would engage the pivot 103. As illustrated in Fig. 1 the effect desired is 90 95 produced by using a bent link 104.

In this form of the apparatus the stationary and movable die members 90 and 91 are provided with suitable co-operating die-casting cavities 109 and also with a well 110 arranged vertically, 100 half thereof being in one die and half in the other. Metal at a suitable temperature and condition is introduced into the well 110 and is displaced by means of a plunger 111 so as to enter the casting cavities 108 and 109 after the movable die member has been pressed against the fixed die member. 105

The metal displaced from the well 110 is forced upwardly through a channel 112 at the side of the well 110 and then into the casting cavities. The 110 plunger 111 should be close to the upper end of the well before it is actuated, and consequently any substantial separation of the plunger from the die or dies should be avoided, thus rendering it difficult to supply hot metal to the well 110 by 115 means of a ladle. However, as indicated, the dies 90 and 91 may be provided at their upper surfaces with a receiving cavity 113 half in each of the dies and connected with the well 110 by means of a passage 114 which is also half in one die and half 120 in the other. In this connection it should be said that the lower end of the passage 114 should be at a higher level than the point of communication between the upright channel and the casting cavities. 125

The plunger 111 may be operated by suitable means including, for example, a cylinder 115 into which the plunger extends, a piston 116 fastened to the upper end of the plunger and pipes 117 and 118 connecting, respectively, the upper and lower 130 ends of the cylinder with suitable means for controlling the fluid pressure at the upper and lower sides of the piston to raise and lower the plunger as desired. In this connection, it may be noted that due to the mounting of the die supports on 135 the bolts 77 and 82, one of which is above the other, the cylinder and plunger are located at one side of the plane of the guide bolts.

The cylinder 115 may be mounted in any suitable manner. For example as illustrated, the cylinder may be mounted on a plate or block 119 secured to the upper edge of the member 83 by suitable means such as screws 120. No provision is made for a fixed support for the plate 119 at the side of the cylinder toward the frame 75, but the movable die-holder 93 is utilized for supporting purposes as by providing the plate 119 with a recess or socket 121 to receive a projection or pin 122 on a block 123 secured to the movable die- 150

holder 93 in a suitable manner as, for example by a screw 124.

The operation of this form of the apparatus is substantially as follows: Assuming that the operating arm 94 is in its right hand (Fig. 1) or forward position, the movable die 91 is separated from the stationary die 90 as it would be just after removing a casting. The arm 94 is then swung counter-clockwise to straighten the toggles and bring the movable die 91 into cooperative engagement with the fixed die 90 as well as move the projection or pin 122, carried by the movable holder 93, into the recess or socket 121 in the plate 119 carrying the cylinder 115.

15 Hot metal in condition to flow is then poured into the receiving cavity 113 and flows through the passage 114 into the well 110. Fluid under pressure is then admitted to the upper part of the cylinder 115 to force down the piston 116 and consequently drive the plunger down into the well 110. This movement of the plunger displaces the metal upwardly through the channel 112 and into the casting cavities 109. The pressure in the upper part of the cylinder is then relieved and fluid under pressure is supplied to the lower end thereof to raise the piston and withdraw the plunger from the well 110. Then the operating arm 94 is swung clockwise to break the toggles and withdraw the movable die with the casting, and the casting is separated from the movable die by suitable ejecting means in the ejector box 92. The machine is then ready for another die casting operation.

It will be seen that machines constructed in accordance with the present invention have many advantages over machines heretofore in general use. For example metals or alloys can be used at temperatures at which they flow thickly, thus enabling die casting to be effected at lower temperatures than usual and the use of metals having higher melting points. Due to the lower temperatures at which die casting can be done by use of the present invention and also due to the short distances through which the metal travels to the casting cavities, impurities including iron in solution are to a great extent eliminated. Similarly aluminum is no longer a necessary constituent of zinc alloys or vice versa, castings may be made more solid because of the higher pressure possible and also the comparatively low temperatures. Other advantages arise from the application of pressure close to the casting and the short or minimum travel required under pressure.

55 The present invention also adapts itself to the use of a plurality of sources of metal supply to the casting as required and to the making of a plurality of castings at one operation. The sizes of the wells may be made to suit the size of the castings and the wells may be replaceable. Also the general arrangement assists in temperature control. It will of course be understood that temperature control of parts of die-casting apparatus has heretofore been obtained by ducts through which liquid is circulated.

It should be understood that various changes may be made in the construction and arrangement of parts and that certain features may be used with others without departing from the true spirit and scope of the invention.

Having thus described my invention, I claim:—

1. In die-casting apparatus, two die members with vertical inner faces provided with casting cavities, a vertical well half in one die member and half in the other and a channel at the side of said well communicating with the upper part of the casting cavities; a plunger to fit in said well; means to depress said plunger and displace hot metal in said well to force it into the casting cavities; and means for separating said die members to remove a casting and for forcing them together preparatory to forming another die-casting. 80

2. In die-casting apparatus, two die members with vertical inner faces provided with casting cavities, a vertical well half in one die member and half in the other and a channel at the side of said well communicating with the upper part of the casting cavities; a plunger to fit in said well; means to depress said plunger and displace hot metal in said well and force it into the casting cavities; and means for separating said die members to remove a casting and for forcing them together preparatory to forming another die-casting and means for supplying metal to said well including a chamber in the upper part of one of said die members and a passage leading downwardly to said well. 90

3. In die-casting apparatus, two die members with vertical inner faces provided with casting cavities, a vertical well half in one die member and half in the other and a channel at the side of said well communicating with the casting cavities; a plunger fitting said well; means to depress said plunger and displace hot metal in said well and force it into the casting cavities; means for separating said die members to remove a casting and for forcing them together preparatory to forming another casting; and means to supply metal to said well including a receiving chamber half in one die member and half in the other, and a passage leading from said chamber to said well. 105

4. In die-casting apparatus, two die members having cooperating sides provided with casting cavities, a well half in one die member and half in the other, an inlet to direct hot metal to said well and a channel at the side of said well communicating with the casting cavities; a plunger to fit in said well; means to depress said plunger and by displacement of hot metal in said well force it into the casting cavities, and means for separating said die members to remove a casting and for pressing them together preparatory to supplying hot metal to said well and forming another die-casting. 110

5. In die-casting apparatus, two die members having inner faces provided with casting cavities, a well half in one die member and half in the other, an inlet to direct hot metal to said well and a channel at the side of said well communicating above the bottom of said well with the casting cavities; a plunger of a cross section to fit said well; means to operate said plunger and by displacement from the well force the metal into the casting cavities; and means for separating said die members for removal of a casting and for forcing them together preparatory to supplying hot metal to said well. 120
